UNITED STATES PATENT OFFICE.

WILLIAM STODDARD, OF LOWELL, MASSACHUSETTS.

IMPROVEMENT IN PLOWING-MACHINES.

Specification forming part of Letters Patent No. 19,215, dated January 26, 1858.

To all whom it may concern:

Be it known that I, WILLIAM STODDARD, of Lowell, in the county of Middlesex and State of Massachusetts, have invented a new and useful Improvement in Plowing-Machines; and I do hereby declare that the following is a full, clear, and exact description thereof, reference being had to the accompanying drawings, and to the letters of reference marked thereon.

In referring to the drawings, Figure 1 denotes an inverted plan or under side view of my machine; Fig. 2, a like inverted end elevation of it; Fig. 3, a side elevation of the same when placed upright and in a working position.

The nature of my invention consists in so constructing a series of plows, with adjustable gage-pulleys connected to the mold-board thereof, as described, for governing the desired depth of furrow, and connecting these plows firmly to endless bands or chains, which are carried by, combined with, and connected to swinging arms and pulleys thereon in such manner that the plows are moved to turn the furrows, and at the same time a constant yielding movement is given the plows, as described, while at the same time the plows are governed to the required depth and to a uniform depth in all uneven or even surfaces of the ground, while they are operated to turn the furrows at right angles with the machine; also, in the arms carrying the plows, which, in addition to their self-adjustment vertically, have a secondary adjustment, whereby they and the plows can be instantly lowered to or raised from the ground for any desired purpose by the operator, these several parts being relatively arranged with each other and the other parts of my machine for operation, all substantially as hereinafter set forth.

To enable persons skilled in the art nearest to which my invention appertains to construct and carry out the same, I will describe it as follows:

I construct a carriage or platform of wood, (seen at A in each of the several figures of the drawings,) which is supported and carried by four wheels, M and M², and which carriage in turn carries or sustains all the other parts of my machine. The smaller or forward wheels, M², are fitted so as to revolve freely upon an axle, r, Figs. 1 and 3. This axle swings upon

the king-bolt or trunnion N², which passes through its center, and is firmly secured to the under and forward portion of the carriage A.

A windlass, v, Figs. 1 and 3, is constructed so as to turn in the carriage A, and is connected by cords n to the axle r, so as to turn or change the direction of the carriage A as desired, by the lever z, which has one of its ends connected to this windlass, while the other is wielded by the hands of the manager for that purpose.

Journal-boxes (seen at O²) are suitably constructed and secured to the platform by means of screws P⁵, Fig. 1, or otherwise. To these boxes is fitted the axle or shaft seen at c, so as to turn freely therein. To each outer end of this shaft the larger or hind wheels, M, are firmly secured for sustaining and carrying jointly with the wheels M² the carriage A and the parts connected thereto.

I construct a driving-shaft, (seen at C,) to which motive power may be applied by windmill B or otherwise, for the operation of my machine. The upper portion of this shaft C turns in the stand Q² and its lower end in the platform A. On and near the lower end of this shaft I secure a bevel-pinion, d, which meshes with and turns the bevel-gear E, of a larger diameter, which is fitted to turn freely on the axle c, and prevented from moving laterally thereon by the rings a a, which are secured to the shaft c.

A clutch (seen at D) is fitted to slide on the shaft c, and prevented from turning, except with the shaft, by a spline, V². This clutch is operated by lever F, the lower end of which is fitted to the groove R² in it, and the upper end of which is pivoted so as to swing on the stand g. It is moved by a reach, H, connected to the lever G, to connect the clutch D and shaft c, with the bevel-gear E, in order that the drive-shaft C may turn them and the wheels M thereon to move the machine about quickly, or for locomotion when the plowing is not being performed.

I will now describe the parts for effecting the plowing; and immediately in connection therewith I construct a shaft (seen at p, Fig. 1) and suspend it so that one of its ends will freely turn in the stand S², which is secured to the under side of the carriage A, and the other end in the lever G. On the shaft p a pulley, P, and

a bevel-gear, O, are secured, which are driven or revolved by the shaft C and bevel-gear E, which meshes with it.

I construct a shaft (seen at N) and suspend it so as to freely revolve in the stands T², which are secured to the under side of the carriage A, Figs. 1 and 2. To this shaft N a pulley, P², is secured for driving one series of plows on one side of the machine, and which is itself driven by belt T from pulley P.

I construct a shaft, (seen at L,) one of its ends being suspended so as to freely turn in the stand V², secured to the under side of the carriage A, while its other end is suspended in the end of the lever G, which has its fulcrum or turning-point on the stud A², which is secured to the stand W², and this stand to the carriage A.

A worm-gear, Q, Fig. 2, is firmly secured to the shaft c, and into this worm-gear Q the worm K is meshed or connected by movement of the lever G for moving along the carriage and plows the width of a furrow onto land, and then, by a contrary movement of the lever G, the worm K is disconnected from the worm-gear Q, and the carriage remains motionless until the next furrow is formed at right angles with the machine, and so on.

The lever G is connected to the lever F by the reach H, so that when this lever G is moved to connect the worm K and worm-gear Q and the bevel-gear O with the bevel-gear E the lever F will previously unclutch the clutch D from the gear E, or when the lever F is moved to connect the clutch D with the gear E the worm-gear Q, worm K, and bevel-gears O and E are disconnected previously to prevent breaking the machine. I place a pulley, P³, on the shaft L, which is driven by a cross-belt, V, for operating the plows in a proper direction. Another pulley, P⁴, is connected to the shaft L, by which one of the series of plows are operated.

I construct two stands, J², and secure on each under side of the carriage A. To each of these stands one end of a strong arm, J, is pivoted and projected outward and at right angles with the carriage A, so as to be self-adjustable to swing freely up and down, (without loosening the belts or chains,) to cause the plows to

sink to the same or a uniform depth in the ground if its surface be regular or irregular.

To the outer end of each arm J a pulley, R, is fitted so as to revolve freely therein. Around these pulleys R and the pulleys P² and P⁴ endless belts or chains W are placed, and propelled by the connection with and turning of the shaft C by any practical motor.

It will be seen that one of the belts W on one side of my machine passes around and is driven by the pulley P², while the other passes around and is driven by the pulley P⁴. (See Fig. 1.) I now construct a number of plows, X, and secure them firmly to the belts or chains W, and provide them with an adjustable crank-shaft, s, passing through the mold-board, and on each side of which I place gage-pulleys e, which can be raised or lowered on the mold-board by the adjustable crank-shaft s, held by set-screws, to give any desired and uniform depth of furrow on even or uneven ground by means of both these adjustable gages e and s and the arrangement of plows X with the arms J in such manner, as within described, that they will at the same time yield of themselves to any inequalities of the ground.

I construct a windlass (seen at m) and place it upon the top of the platform A. This windlass is connected with the outer ends of the arms J by the cords i, so that the plows X can all be instantly raised either out of the ground or lowered into the ground by turning the windlass crank, which is under the control of the operator, all as hereinbefore set forth.

What I claim as my invention, and desire to secure by Letters Patent, is—

Constructing the plows X with an adjustable depth-gage, e and s, attached to the mold-board thereof in the manner described, when such plows are connected (for operation) to an endless chain or band, in combination with the flexible arms J, which carry the plows X and band W, essentially in the manner and for the purposes fully set forth and described.

WILLIAM STODDARD.
